UNITED STATES PATENT OFFICE.

SVEND M. MEYER, OF BROOKLYN, NEW YORK, ASSIGNOR, BY MESNE ASSIGNMENTS,
OF THIRTEEN-FORTIETHS TO SVEND M. MEYER, OF WOODHAVEN, NEW YORK, AND
TWENTY-SEVEN FORTIETHS TO WILLIAM JAMES, OF BROOKLYN, NEW YORK.

HAND ARC LAMP.

Application filed February 20, 1926. Serial No. 89,696.

The object of my improvement is a hand arc lamp, particularly for the purpose of reflecting light onto objects to be photographed and for all purposes where continuous operation of the lamp is not required. For instance for photographic purposes it is seldom necessary to operate such a lamp more than one-half or one minute, though the improvements made by the present invention permit much longer operation with the hand control mechanism shown and described. The novel combination of elements of which this lamp is constituted permits an easy handling of the lamp without separate accessory parts such as resistance or choke coils or the like, all that is necessary to put the lamp into operation being the connection of the lamp by a flexible cord to any commercial electric supply circuit whether this be alternating or direct current. The advantages accruing from this novel combination greatly increase the use of such lamps for portable purposes, inasmuch as owing to its comparatively small size it can easily be carried in a coat pocket.

My invention is illustrated in the accompanying drawings in which—

Figure 1 represents a side elevation of a hand arc lamp according to my invention, portions thereof being shown in longitudinal vertical section on the line 1—1, Figure 2;

Figure 2 represents a top view of the lamp;

Figure 3 represents a front view seen from the direction in which the light is reflected;

Figure 4 is a transverse section of the carbon release mechanism taken on the line 4—4, Figure 3;

Figure 5 is a longitudinal vertical section of this mechanism taken on the line 5—5, Figure 4; and

Figure 6 is a bottom view of the lamp, the protecting casing being removed.

Referring to Figures 1, 2 and 3, 1 is a base plate on which are mounted, insulated therefrom by bushings 2^a, two carbon holders 2 and 3 by means of screws 4. In order to frictionally hold the carbons 14 inserted in these holders, the latter are castellated at their free ends as shown at 15 so that these ends may yieldingly press against the

carbons. On another portion of base plate 1 is mounted a standard which consists of two tubular elements 5 and 6 braced by a handle 7 also mounted on base plate 1 as shown. Standards 5 and 6 and handle 7 are sufficiently rugged to permit the carrying of the entire lamp by means of handle 7. Tubular standards 5 and 6 contain each a plunger 8 and 9 respectively which are coupled together by means of a bracket 10 which is forked as shown in Figure 2 and carries at each of its forked ends a holder 11, 12, respectively for the upper carbons 13 which cooperate with the lower carbons 14 to produce the arc in the well known manner.

Upper carbons 13 each are freely slideable in their respective holders so that they will drop by their own weight onto the lower carbons 14. plungers 8 and 9 which thus support thru the bracket 10 the two upper carbon holders together with their carbons are counter-balanced by springs 16 housed in the tubular standards, the tension of these springs being sufficient to push the plungers by means of detent 17 against the adjustable stop 18 mounted on one of the standards. This serves as a limit on the uppermost position which the upper carbon holders may assume for a certain adjustment made at 18. Detent 17 which is fixed to plunger 9 protrudes thru a slot 19 provided in standard 6.

The means for holding the upper carbons 13 in their respective holders 11 and 12 in a desired position are as follows.

These carbon holders, for instance 11 in Figures 1, 4 and 5 have a portion of the side wall cut away such as is shown for instance in Figure 5, at 30, so that the carbon is exposed at that portion to the outside. A shackle 31 loosely pivoted to a bracket 32 fixed to the carbon holder extends across cut-away portion 30 of the holder so that it is enabled to frictionally contact with the carbon. A tension spring 33 fastened to the free end of shackle 31 is fastened at its other end to bracket 10 as will appear from Figures 1 and 2 so that shackle 31 is thereby held against carbon 13 preventing it from slipping down in its holder. A fixed guide 34 is fastened to the bracket 32 and extends past shackle 31, following substantially its contour a slight distance away from it how-

ever, and extending with its right-angularly bent end into an opening 35 provided at the free end of shackle 31. This guide merely has the purpose of preventing the free end 5 of shackle 31 from moving up and down, though a certain slight play is permitted for shackle 31.

The upper carbons together with bracket 10 can be moved down against the tension 10 of springs 16 in standards 5 and 6, when the operator, holding the lamp on handle 7 with the four fingers of his hand, presses his thumb onto thumb disk 36. The upper carbons are thus moved until they contact 15 with the lower carbons so that the arc is struck as soon as the operator releases thumb disk 36. Inasmuch as the two sets of carbons will not burn off evenly it would happen that the one pair of carbons is brought 20 in contact when thumb disk 36 is depressed for the purpose of striking the arc whereas the other pair which happens to have burned off more during the previous use of the lamp would still remain out of contact so that the 25 arc cannot be struck in either pair, the two pairs of carbons being connected in series with each other as will be referred to in detail later on. To avoid this the following 30 means are provided for each upper carbon holder. Adjacent to the free end of each shackle 31 a tripping finger 37 is located and fastened at its rear end to the standards 5 and 6. This free end is slightly rounded off as shown at 38 and extends sufficiently 35 close to the free end of shackle 31 that when the upper carbon holders are depressed as previously described, the shackle end will strike rounded off portion 38 short of its extreme end so that when the upper carbon 40 holders are further depressed shackle 31 in following the cam surface 38 will be lifted off its carbon 13, enabling the latter to freely drop down thru its holder until it strikes the lower carbon. If now thumb disk 36 is 45 released both upper carbons are simultaneously removed from their lower carbons and both arcs will be struck at the same time, and whenever the upper carbon holders arrive at their extreme upper portion, the 50 distances between the two pairs of carbons, i. e., the two arcs, will be of the same length. During the operation of the lamp the operator can follow up with the upper carbons by slightly pressing onto thumb disk 36 to 55 maintain the arc approximately at the same length, or if he should momentarily desire to have greater light intensity he may even temporarily shorten the two arcs.

The shackles 31 remain removed from 60 their respective carbons so long as each shackle is engaged by its cam surface 38 and they lock the carbons in their holders as soon as thumb disk 36 is raised for the purpose of striking the arc. For slightly 65 increasing the weight of the upper carbons

and for the purpose of properly fastening the connecting pig tail 53 to these carbons heavy rings 39 are attached to the upper ends of carbons 13.

The cylindrical reflector 40 is removably 70 attached to standards 5 and 6 by means of a thumb screw 41. It is desirable to have this reflector removably attached to the lamp so as to facilitate the packing of the lamp into the closest possible space. 75

For steadyng the arcs and for cutting down excessive voltages which may exist in the supply line to which the lamp is connected, for instance 110 volt, to the desired amount at which the arcs may best function, 80 I provide ballast coils disposed beneath the base plate 1 of the lamp and wound of resistance wire in such fashion that they may serve at the same time as choke or ballast coils in case the lamp is supplied with alternating current. These coils may best be seen in Figure 6 with regard to their arrangement relatively to each other. I have provided three coils 45, 46 and 47. The two coils 45 and 46 are arranged near the outer 85 edge of base plate 1 and are both wound alike with an odd number of layers each, in the present case three layers of which two layers are counter-wound relatively to each other so that the respective magnetic fields produced by them will neutralize each other. The third layer is then the only layer which is inductively effective. It is of course obvious that more than three layers may be used so long as a certain number of layers is wound opposite to an equal number of the other layers and so that only the remaining layers of the total number remain inductively effective. The purpose of this arrangement is that, for instance by using 90 three layers I am enabled to use a very heavy resistance wire which would not unduly heat at the current load used for the comparatively short time during which the lamp burns. Such a heavy resistance wire being 95 of course quite long in order to produce the resistance required, would when coiled up thruout its entire length in a coil wound thruout in the same direction produce too great an inductive effect. In case of direct 100 current these coils act purely as ohmic resistances, and owing to the low specific current load which the wire has to carry these coils will not unduly heat. The center coil 105 47 is wound thruout with a similar heavy 110 resistance wire in the same direction, however, for all layers, but for cooling purposes the coil is comparatively long and the layers are arranged in banks such as is shown 115 at 47^a.

The circuit connection of these coils with the carbons and the supply line is as follows. Two plug pins 50 and 51 are fixed in a block of insulating material 52 at the rear end of the lamp and the current passes 120 125

from plug pin 51 thru coil 46 thence thru lower carbon holder 2 thence thru the lower and upper carbon 14, 13, thence thru pig tail 53 to the other pair of carbons down 5 to lower holder 3 and thence over coil 47 and thru coil 45 to plug pin 50. The two outer coils 45 and 46 are arranged with respect to the polarity of the field produced by them such that adjacent ends of the coils have the same polarity, whereas the center coil 47 extends with its thin end to about the center of the two outside coils and is wound in such a direction that the polarity at this inner end of the coil is opposite to the polarity of the ends of the outer coils pointing in that direction. For instance I have indicated the polarity of the ends of the outside coils adjacent to the connecting plug with N, N and accordingly the end of coil 20 47 pointing in the same direction should have a south polarity which I have illustrated with S. By thus arranging the coils I avoid an excessive chattering of the lamp when supplied with alternating current.

25 For the purpose of protecting the ballast coils a perforated casing 55 is attached to the lower side of base plate 1 as may be seen in Figures 1 and 3.

While I have shown and described a lamp provided with two sets of carbons, I do not wish to limit myself to this number, inasmuch as additional sets may be provided, each set having a release mechanism such as shown and described and hand operated from a common point conjointly and coextensively with the mechanisms of the other sets.

I claim:—

1. A hand arc lamp having two pairs of vertically disposed carbons mounted side by side and being electrically connected in series with each other, a stationary holder for the lower carbon of each pair and a hand controlled vertically moveable bracket and holder for the upper carbons mounted on said bracket, a guide for said bracket and a spring supporting said bracket and tending to hold it in raised position, a spring pressed shackle for each upper carbon holder normally engaging the carbon contained therein to prevent it from freely sliding, a tripping arm for each shackle disposed to lift it from its carbon when the bracket is depressed beyond a predetermined amount to permit the upper carbon to freely slide into contact with its lower carbon and an adjustable stop for controlling the upward movement of said bracket and steadyng resistances disposed in the lower portion of said lamp and being electrically connected in circuit with said carbons.

2. A hand arc lamp having at least one pair of superposed carbons, a base plate, a stationary holder for the lower carbon, mounted on and insulated from said plate and a hand controlled vertically moveable holder for the upper carbon, also mounted on and insulated from said plate, means for normally holding the upper carbon in position in its holder, means for disengaging said holding means from said carbon when its holder is moved more than a predetermined amount towards the lower carbon to permit the upper carbon to freely slide onto the lower carbon, and three steadyng impedance air core coils wound of suitable resistance wire and arranged beneath said base plate and in circuit with said carbons, two of said coils having less than half the total number of their layers counter-wound relatively to a similar number of the remaining layers to reduce the impedance effect of the total number of layers for a given length of resistance wire contained in the coil, the third of said coils being bank wound, the two counter-wound coils being placed with similar poles adjacent to each other and one end of the bank wound coil extending longitudinally midway between the other coils, said coil end having a polarity opposite to that of the ends of the outer coils pointing in the same direction for the purpose set forth.

SVEND M. MEYER.
